(57) **CLAIM**

The ornamental design for a charging connector for electric vehicles, as shown and described.

DESCRIPTION

FIG. 1 is a top, front, right side perspective view of a charging connector for electric vehicles showing our new design;

FIG. 2 is a bottom, rear, left side perspective view thereof;

FIG. 3 is an enlarged front elevation view thereof;

FIG. 4 is an enlarged rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" (identified in FIG. 1), shown at a greater scale for clarity of disclosure; and, FIG. 10 is an enlarged view of detail "10" (identified in FIG. 5), shown at a greater scale for clarity of disclosure.

The dash-dash broken lines shown in the drawings depict portions of the charging connector for electric vehicles that form no part of the claimed design. The dash-dot broken lines illustrate the boundaries of the enlarged portions and form no part of the claimed design.
